ATTORNEY

UNITED STATES PATENT OFFICE

GEORGE LESLIE SMITH, OF ROCK ISLAND, ILLINOIS

COIN BOX

Application filed October 28, 1929. Serial No. 403,000.

This invention relates to a coin box which is mainly designed for use with the apple vending machine forming the subject matter of an application filed by me on April 5, 1929, Serial No. 352,851.

The general object of this invention is to provide means for ringing a bell when coins are dropped into the box and for providing a weighted member forming the bottom of a transparent chamber so that the coins on the member can be seen, the member tilting to discharge the coins when a certain number of coins is placed thereon, so as to deposit the coins in a drawer.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a vertical sectional view through the device.

Figure 2 is a section on line 2—2 of Figure 1.

In these views, the numeral 1 indicates a casing, the top of which is adapted to be connected to a support 2 which may be a part of the apple vending machine shown in the before mentioned application. This casing contains an opening in one side thereof so that a coin receiving drawer 3 may be placed in the lower part of the casing and the casing and drawer are formed with projections 4 having holes therein to receive part of a lock 5 so that the drawer can be locked in closed position.

The support 2 has an opening therein surrounded by an upwardly extending flange 6 which is spaced from the walls of the opening to form a holder for the lower end of a transparent cylinder 7, the top of which is closed by a cover 8. A rod 9 passes through a central hole in the cover and has its upper end upset to form a head which engages the cover.

The lower end of the rod passes through a hole in a cross piece 10 of substantially yoke shape, with its ends connected with the support 2. The lower end of the rod is threaded to receive a nut 11 which holds the parts assembled. A disk 12 is pivoted at its center to the rod and a weight 13 on the disk acts to hold the same in horizontal position, with a part engaging a stop 14 on the rod. When in this position, the disk forms a bottom for the cylinder 7. A bell 15 is fastened to the upper part of the rod by a set screw 16 and a coin slot 17 is formed in the cover.

Thus when a coin is dropped through the slot 17, it will strike the bell and sound the same and then the coin will drop on the disk 12. When a certain number of coins is dropped upon the disk, their weight will overbalance the disk and cause the same to tilt, as shown in dotted lines in Figure 1, so that the coins will slide off the disk and fall into the drawer 3. Thus one can tell by looking into the device whether or not he has deposited the sum of money for the articles which he desires to remove from the vending device. As will be understood, this device is used in the honor system of vending machines, where the honesty of the customer is relied upon for placing the correct amount of money in the coin box to cover the articles removed from the vending machine.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A coin box comprising a support having an opening therein, a transparent member resting on the support and surrounding the opening, a cover for the transparent member having a slot therein, a cross piece depending from the support under the transparent member, a rod passing through the cover and through said cross piece for holding the parts assembled, a bell on the rod adapted to be struck by the coins dropped into the slot, a

disk pivoted to the rod and forming a bottom for the transparent member, a weight on the disk, a stop on the rod whereby the weight normally holds the disk in horizontal position, said disk tilting under the weight of coins collecting thereon, a casing depending from the supporting member and surrounding the opening in the supporting member and a drawer in the casing for receiving the coins dropping from the disk.

10 In testimony whereof I affix my signature.
GEORGE LESLIE SMITH.
